UNITED STATES PATENT OFFICE.

ROSCOE C. HOFFMAN, OF INDIANAPOLIS, INDIANA.

DISK-WHEEL CONSTRUCTION.

1,387,982.

Specification of Letters Patent. Patented Aug. 16, 1921.

Application filed July 6, 1920. Serial No. 394,240.

To all whom it may concern:

Be it known that I, ROSCOE C. HOFFMAN, a citizen of the United States, and a resident of Indianapolis, county of Marion, and 5 State of Indiana, have invented a certain new and useful Disk-Wheel Construction; and I do hereby declare that the following is a full, clear, and exact description thereof, reference being had to the accompanying 10 drawings, in which like numerals refer to like parts.

This invention relates to the construction of disk wheels for vehicles, and more particularly to the laminated type as set forth 15 in my former Patent No. 1,341,465, issued May 25, 1920.

The particular feature of this invention consists in the manner of disposing the axial or bracing disks with respect to the supporting disk, whereby a supporting disk formed 20 of sheet metal of the same thickness throughout may be reinforced and braced near the hub in such a manner that the supporting disk will form the complete outer surface 25 of the wheel, and the smaller bracing disk will be inclosed between said supporting disk and the larger bracing disk. By this manner of construction a wheel of equal strength and durability to a rolled disk tapering radially from its center, is secured, without the 30 difficulty of manufacture, and will present the same clean and solid appearance.

The full nature of this invention will be understood from the accompanying drawings and the following description and claims.

Figure 1 is a radial section through a laminated disk wheel. Fig. 2 is the same as Fig. 1 showing a modified form thereof. 40 Fig. 3 is the same as Fig. 1 showing a further modified form. Fig. 4 is a radial section through a modified type of disk wheel.

In the drawings there is a portion of a disk wheel having a supporting disk 10, of 45 equal thickness throughout, formed, preferably by stamping, into the shape of a disk wheel with an inwardly turned rim flange 11 and a hub flange 12 adapted to be engaged by a tapered bolt 13 which secures it 50 rigidly to the hub member 14. In order to resiliently strengthen and brace the main supporting disk 10, particularly around the hub and centrally between the hub and rim, there is provided an auxiliary bracing disk 55 15 having substantially the same dish as the

supporting disk, and having a little over half the radius thereof, which is mounted on the inside of said supporting disk with its inner hub flange portion 16 rigidly held between the bolt 13 and hub member 14 in 60 the same manner as the supporting disk 10. To further strengthen and resiliently brace the supporting disk there is an inside bracing disk 17 of about half the radius of the disk 15, and of substantially the same form 65 which is clamped into position between the disk 15 and supporting disk 10, adjacent the latter and spaced from the former by the spacing member 18. The three disks and the spacing member may be welded or riveted 70 together within the hub, if desired, in any suitable manner. The disks 15 and 17 are formed with less dish than the supporting disk 10 so that, when they are mounted therewith and secured in position, there will 75 be a spring tension causing an outwardly directed force against said supporting disk. By means of this construction the supporting disk is braced against lateral stress and strain directed inwardly, and its outwardly 80 dished form protects it from any distortion or collapsing in that direction. The disk 15 covers and protects the smaller disk 17 and the spacer 18 so that they are hidden from view and protected from the elements. 85

In Fig. 2 a form of disk wheel is shown differing only from that above described in that there is provided an annular offset or shoulder 19 in the disk 10 against which the periphery of the disk 15 abuts. The annular shoulder 19 is adapted to limit the movement of the disk 15 so that the disk 15 will act in the manner of a brace for strengthening any lateral and inwardly directed thrust. 90

In Fig. 3 a further modified form is shown wherein the construction is similar to that shown in Fig. 2 excepting that the inner disk 17 is eliminated and supplanted by a spacer 180 of double the thickness of the spacer 18. 100 This construction forms a lighter and less expensive type of wheel, but one of less strength than that shown in Fig. 2.

In Fig. 4 a modified form is shown in which the disk 10 is stamped with a plurality of pockets or flutes 20 so as to form a rim 110 as described in my patent for disk wheel for vehicles No. 1,376,938, issued May 3, 1921. The center of the disk 10 is turned inwardly so as to form the hub supporting 110

flange 21, and is covered with the sheet metal disk 22 for covering up the hub and pockets 20. The reinforcing or bracing disk 150 is mounted on the inside of the wheel and is 5 provided with an outwardly extending annular bearing 23 integral therewith which telescopes the hub flange 21 of the disk 10 and has its outer edge turned back so as to clamp the disk 22 at 24. The periphery of 10 the disk 150 lies adjacent to and abuts the disk 10 at the bend therein, wherein the pockets or flutes merge into the disk, the disk 150 acting as a resilient bracing member in the same manner as the disks 15 above 15 described, and may, or may not be welded at 25.

The disks 15, 17 and 150 as above specified are formed with a lesser dish than the supporting disk 10 and, therefore, there is a 20 continuous outward thrust about the periphery of said disks when they are secured to the hub members.

The invention claimed is:

1. A disk type wheel for vehicles including 25 a supporting disk adapted to carry a tire rim about the periphery thereof, an auxiliary bracing disk mounted adjacent said supporting disk having its outer periphery in engagement therewith, said bracing disk 30 being mounted at an angle to said supporting disk so as to act as an angular brace therefor, and an intermediate disk of less radius than said auxiliary bracing disk mounted between said auxiliary disk and 35 supporting disk for further bracing and strengthening said supporting disk near the center portion thereof.

2. A disk type of wheel for vehicles including a supporting disk adapted to carry 40 a tire rim about the periphery thereof, an inwardly extending annular shoulder formed in said supporting disk, an auxiliary bracing disk mounted adjacent said supporting disk having its outer periphery abutting 45 said shoulder, said bracing disk being mounted at an angle to said supporting disk so as to act as an angular brace therefor, and an intermediate bracing disk mounted between said auxiliary and sup-

porting disks of less radius than said auxiliary disk for further strengthening and bracing said supporting disk near the center thereof.

3. A disk type of wheel for vehicles including a supporting disk adapted to carry 55 a tire rim about the periphery thereof, an inwardly extending annular shoulder formed in said supporting disk, an auxiliary bracing disk mounted adjacent said supporting disk having its outer periphery abutting said 60 shoulder, said bracing disk being mounted at an angle to said supporting disk so as to act as an angular brace therefor, and an intermediate bracing disk mounted between said auxiliary and supporting disks of less 65 radius than said auxiliary disk and having its outer periphery bearing against said supporting disk for further strengthening and bracing said supporting disk near the center thereof, and means mounted between 70 said supporting and auxiliary bracing disk for spacing them apart whereby they will extend axially at an angle to each other.

4. A disk type of wheel for vehicles including a supporting disk adapted to carry 75 a tire rim about the periphery thereof, an inwardly extending annular shoulder formed in said supporting disk, an auxiliary bracing disk mounted adjacent said supporting disk having its outer periphery abutting said 80 shoulder, said bracing disk being mounted at an angle to said supporting disk and welded thereto about its outer periphery so as to act as an angular brace therefor, and an intermediate bracing disk mounted between 85 said auxiliary and supporting disks of less radius than said auxiliary disk and having its outer periphery bearing against said supporting disk for further strengthening and bracing said supporting disk near 90 the center thereof, and means mounted between said supporting and auxiliary bracing disk for spacing them apart whereby they will extend axially at an angle to each other.

In witness whereof I have hereunto affixed my signature.

ROSCOE C. HOFFMAN.
